SHOE SOLE

Gonzalo Mediano Capdevila, Buenos Aires, Argentina, assignor to Coturno, S. A., Caracas, Venezuela, a corporation of Venezuela

Application February 5, 1951, Serial No. 14,104

Term of patent 14 years

(Cl. D7—5)

To all whom it may concern:

Be it known that I, Gonzalo Mediano Capdevila, a citizen of Spain, and a resident of Calle Larrea No. 735, Buenos Aires, Argentina, have invented a new, original, and ornamental Design for a Shoe Sole, of which the following is a specification, reference being had to the accompanying drawings, forming a part thereof.

Fig. 1 is a bottom plan view of the shoe sole, showing my new design.

Fig. 2 is a longitudinal sectional view taken on line 2—2 of Fig. 1 and looking in the direction of the arrows.

I claim:

The ornamental design for a shoe sole, substantially as shown.

GONZALO MEDIANO CAPDEVILA.
